UNITED STATES PATENT OFFICE.

GROVER C. VOIT, OF HOPEDALE, OHIO.

RAIL CHAIR OR TIE.

Application filed September 18, 1928. Serial No. 306,622.

The present invention relates to a rail chair or tie designed for supporting the rails of mobile machinery or cars, and the prime object of the invention resides in the provision 5 of a device of this nature having incorporated therein features for cushioning the rails.

Another very important object of the invention resides in the provision of a chair for a rail which is provided with rubber 10 cushion seats on which the rail rests.

With the above and numerous other objects in view, as will appear as the description proceeds, the invention resides in certain novel features of construction, and in the combination and arrangement of parts as will be hereinafter more fully described and claimed.

In the drawing:

Figure 1 is a top plan view of a chair embodying the features of my invention, showing a rail supported therein.

Figure 2 is a side elevation thereof.

Figure 3 is a perspective view of one of the wedge holding members.

Figure 4 is a perspective view of one of 25 the rubber cushion sheets.

Figure 5 is a longitudinal section, taken substantially on the line 5—5 of Figure 1.

Figure 6 is an end elevation of the chair.

Figures 7 and 8 are transverse sections 30 taken substantially on the lines 7—7 and 8—8 respectively of Figure 2, and

Figure 9 is a perspective view of the chair with the rubber seat cushions removed.

Referring to the drawings in detail, it will 35 be seen that the present embodiment of the invention includes a base plate 5 with longitudinal flanges 6 rising therefrom, spaced in parallelism with the longitudinal side edges thereof. End transverse flanges 7 rise from 40 the base plate 5 but terminate short of the upper edges of the flanges 6. The flanges 6 are provided with extensions 8 having openings 9 therein, to receive wedge members 10 which are provided with spaced apertures as 45 is indicated at 11, so that cotter pins or the like 12 may be used for holding the wedge members in place, while at the same time to provide extensibility to compensate for vary-

ing thicknesses in the base of the rail, as is clearly indicated in Figures 6 and 7.

A plurality of sheets 14 of rubber rest on the plate 5 between the flanges 6 and 7 throughout the length of the base plate. A single sheet may be used, if desired. The rail rests on these seat cushions 14, and the wedge members 10 hold the rail tightly down on the cushions. Thus the rail is free to give under the weight of heavy mobile machinery, such as steam shovels, heavy freight cars and the like, and the rubber cushions will absorb considerable of the shock, vibrations and the like.

It is thought that the construction, utility, and advantages of this invention will now be quite apparent to those skilled in this art, without a more detailed description thereof.

The present embodiment of the invention has been disclosed in considerable detail merely for the purposes of exemplification, since in actual practice it attains the features 70 of advantages enumerated as desirable in the statement of the invention and the above description. It will be apparent that changes in the details of construction, and in the combination and arrangement of parts may 75 be resorted to, without departing from the spirit or scope of the invention as hereinafter claimed or sacrificing any of its advantages.

Having thus described my invention, what I claim as new is:

A rail chair of the class described including an elongated base plate having longitudinal flanges rising therefrom in spaced relation to each other, and a seat of rubber cushion material on the base plate between the flanges, said flanges being provided with openings, and wedge members insertable through the openings to engage the base of the rail to clamp the same down on the seat, and detachable means anchored in said wedge 85 members and abutting said flange for locking said wedge members in varying transverse 90 positions.

In testimony whereof I affix my signature.

GROVER C. VOIT.
